UNITED STATES PATENT OFFICE.

ROBERT J. ANDERSON, OF SEWICKLEY, PENNSYLVANIA, ASSIGNOR TO NATIONAL FIREWORKS, INC., A CORPORATION OF MASSACHUSETTS.

FLOAT LIGHT.

Application filed June 23, 1927. Serial No. 200,792.

My invention relates to improvements in the construction of torches made essentially of pyrotechnic substance and adapted to burn for a substantial interval of time. The invention finds practical application in float-lights, which are torches made suitably buoyant and adapted to be dropped from aircraft to the sea, and being so dropped, to float and burn, emitting light. In that particular application I shall show my invention and describe it.

In the accompanying drawing Fig. I shows in vertical and axial section so much of the float-light structure as includes the pyrotechnic substance in its case, and the means associated with it whereby ignition is accomplished and effective burning insured. Figs. II and III are views in plan and in cross-section of a particular detail of the structure.

An essentially cylindrical body 1 of suitable buoyant material, which as a matter of practice is wood of relatively soft and light nature, is provided with an axial bore 2. This body assumes in service the vertical position in which it appears in the drawing. The bore is throughout the greater portion of its extent and from the lower end upward, of uniform diameter. At a short interval upward from the lower end an annular offset 3 is formed, interrupting the uniformity. The bore is prolonged upward in a narrow continuation 4, which in this instance is narrower than the portion 2, and this upward prolongation constituted, as presently will more clearly appear, the orifice through which the pyrotechnic burns. From the upper end the light-giving flame emerges. At the upper end the main and charge containing portion of the bore is continued in a region where the bore is widened, as indicated at 5. This widened region serves as a gas chamber, as presently will appear, and its rearwardly facing wall 6, formed where the bore narrows again constitutes a shoulder against which a certain spring bears. I have said that in Fig. I so much of the structure is shown as constitutes the case for the pyrotechnic. It will be seen that at its lower end the wooden body 1 by means of an offset is shaped to slightly diminished diameter. Those acquainted with such structures will recognize in this offset a seat upon which a

head which closes from below the hollow space within, is secured to the body 1.

The pyrotechnic substance itself in the form of cylindrical pellets 7 with axial bore fits snugly in the bore 2 of the body 1. These pellets together with their starter charge 8 fill the bore throughout its main portion 2. They rest downwardly upon a barrier 9 secured in offset 3, and to such position they are yieldingly held by the tension of a spring 10, just alluded to, which, bearing upon surface 6, exerts its pressure downwardly upon the charge in the portion 2 of the bore. Extending through a central opening in barrier 9 and through the bore formed in pellets 7 and into the substance of the starter charge 8 extends a fuse 11. This fuse at its outer and lower end is adapted to be fired by known means, and is here shown to be encased in a length of copper tubing 12 crimped to place upon it. At its inner end and within the substance of the starter charge 8 the fuse 11 is provided with a V-shaped recess, in which is set a quick-match 13.

The starter charge 8, which is a slow-burning combustible powder, containing within itself the elements essential to combustion and generating as it burns little or no gas, is contained in a cup 14, conveniently formed of zinc, and the charge within the cup is faced with a wad or closing disk 15, which may conveniently be of fibre.

The essential operation consists in the progress of the following steps: the burning of the fuse 11, which is ignited at its lower and protruding end; the firing of the quick-match 13; the consequent burning of the starter charge 8; and the ignition of the pyrotechnic pellets themselves, beginning at the upper end. As the pyrotechnic burns the wad 15 is consumed and a flame emerges from the upper end of bore 4. The pyrotechnic is such in composition and the proportions of its body are such as to afford a flame of proper brilliance and continuing for an adequate interval of time. When the ignited and falling torch plunges beneath the surface of the sea, the gases generated by combustion are effective to prevent ingress of water through bore 4 and consequent extinction of the flame.

My invention is found, first in the mounting of the charge. It is supported as has been said on barrier 9 and is held downwardly

to its position against barrier 9 by spring 10. Barrier 9, as particularly shown in Figs. II and III, in a disk of steel in which a central circular opening has been cut to form an annulus. This annulus is slit through radially or substantially radially at 90, and then the annulus is crushed or collapsed to conical shape with ends overlapping. Its perimeter by such collapsing is reduced to 5 a circle of smaller size, and of a size permitting introduction into bore 2, and in such collapsed condition the annulus is inserted 10 behind a charge introduced within bore 2. By pressing it against the charge within bore 15 2, the annulus is expanded, enlarging its perimeter enters the off-set 3, and the expanded annulus then constitutes a lock, securing the charge within the bore. The annulus adjacent and on either side the slit is 20 provided with holes 91, and after it has been applied and expanded a proper instrument inserted into bore 2 from below may be made to engage the holes 91 and through such engagement the instrument may effect the collapse 25 of the annulus again, that it may be removed. Thus the structure may be loaded, unloaded, and loaded again, without destruction of any of the parts, and yet when loaded the charge is secure in its place. The annulus 30 9 when in place is advantageously faced with a washer of suitable material such as fibre, against which the pyrotechnic material immediately bears.

The charge of pyrotechnic made up as ordinarily it will be of a succession of pellets 35 7 together with its starter charge 8, is compacted, its parts are held to contact one upon another, and the whole is held to abutment downward upon the washer faced barrier 9, by the spring 10. Such yielding means for holding the charge in place have advantage, not only in that compensating for all irregularities they secure the parts in positive contact, but also because they allow expansion. 40 45 The pellets as they burn tend to elongate, and by making provision for elongation, a certain mushrooming of the material is prevented and the charge burns more freely and with better effect. Clogging with ash is avoided.

The widening of the bore at 5 affords at 50 the upper end of the charge a gas chamber of relatively large size (the chamber against whose upper wall 6 the spring 10 bears). The presence of this chamber-like enlargement of 55 the bore at its upper end has the effect of relieving somewhat and lessening the gas pressure which with the burning of the pyrotechnic material mounts up within the bore; and

in consequence of such avoidance of higher pressure, the burning of the pyrotechnic material will progress slowly and the duration of its time of burning will be prolonged. 60

The quick-match 13, it will be remarked, is set in the side of the cylindrical fuse body 65 11. This lateral position of the quick-match makes for the more certain ignition of the starter charge; for, in case the quick-match fails (and this sometimes happens) yet the fuse burning to the end against a wall of 70 starter charge material, is more apt itself to effect ignition.

I claim as my invention:

1. In a pyrotechnic torch the combination with a body adapted to contain and carry the charge as it burns and to that end possessing a charge-containing chamber formed within it, an abutment within the chamber adapted to sustain a charge, and yielding means within the chamber adapted to engage a charge and hold it as it burns to place upon said abutment. 75 80

2. In a pyrotechnic torch the combination with a body in which is formed a cylindrical charge-containing chamber, opening from the rear, an abutment in the form of an expandable and contractible split annulus of metal adapted to be secured in the wall of such charge-containing chamber and means within the chamber for holding a charge to 85 90 position upon said abutment.

3. In a float-light structure a cylindrical body with axial and shouldered bore, a split annulus of metal expandable and collapsible to and from peripheral engagement with the 95 wall of the bore, and a spring arranged with positive bearing within said shouldered bore, said annulus and spring cooperating to secure a charge brought to place between them. 100

4. In a pyrotechnic torch the combination with a body in which is formed a charge-containing bore and a flame orifice opening from such bore, the bore being widened adjacent the flame orifice, and means for securing a charge of pyrotechnic material yielding within such bore. 105

5. The structure of claim 4, the securing means including a spring arranged in the widened portion of the bore.

6. In a pyrotechnic torch a charge of pyrotechnic material, a starter charge, a fuse with cylindrical body extending into said starter charge, and a quick-match set laterally in the cylindrical body of said fuse. 110

In testimony whereof I have hereunto set 115 my hand.

ROBERT J. ANDERSON.
